KIT FOR PHYSICIANS' AND SURGEONS' SUPPLIES OR SIMILAR ARTICLE

Edward J. Palczewski, Philadelphia, Pa.

Application July 3, 1953, Serial No. 25,797

Term of patent 14 years

(Cl. D58—13)

To all whom it may concern:

Be it known that I, Edward J. Palczewski, a citizen of the United States, residing in the city of Philadelphia, in the county of Philadelphia, State of Pennsylvania, have invented a new, original, and ornamental Design for a Kit for Physicians' and Surgeons' Supplies or Similar Article, of which the following is a specification, reference being had to the accompanying drawings forming part thereof.

Fig. 1 is an exploded perspective view of a kit for physicians' and surgeons' supplies or similar article, showing my new design;

Fig. 2 is a top plan view thereof;

Fig. 3 is a front elevational view thereof;

Fig. 4 is a side elevational view thereof, taken from the right side of Fig. 1; and

Fig. 5 is a side elevational view thereof, taken from the left side of Fig. 1.

I claim:

The ornamental design for a kit for physicians' and surgeons' supplies or similar article, as shown.

EDWARD J. PALCZEWSKI.
